No. 792,879.

PATENTED JUNE 20, 1905.

D. D. CASEY.

FAUCET.

APPLICATION FILED OCT. 15, 1904.

UNITED STATES PATENT OFFICE.

DENNIS D. CASEY, OF SPRINGFIELD, MASSACHUSETTS.

FAUCET.

SPECIFICATION forming part of Letters Patent No. 792,879, dated June 20, 1905.

Application filed October 15, 1904. Serial No. 228,516.

To all whom it may concern:

Be it known that I, DENNIS D. CASEY, a citizen of the United States of America, and a resident of Springfield, in the county of Hampden and State of Massachusetts, have invented certain new and useful Improvements in Faucets, of which the following is a full, clear, and exact description.

This invention relates to improvements in valves, and more particularly beer cocks or faucets.

The object of the invention is to provide a beer cock or faucet in which the valve opening and closing devices are practical, efficient, and durable.

The invention consists in constructions and combinations of parts, all substantially as hereinafter fully described, and set forth in the claims.

20 The improved valve (illustrated as a beer-cock) is shown in the accompanying drawings, in which—

Figure 1 is a central horizontal sectional view therethrough. Fig. 2 is a partial section taken on the same plane as Fig. 1 and showing the cock in its opened position. Fig. 3 is a side view of the lower or nozzle end of the cock. Fig. 4 is a sectional view at right angles to the section Fig. 1 and as taken on the line 4 4. Fig. 5 is a horizontal cross-section on line 5 5. Fig. 6 is a perspective view showing parts in detail and as separated from their coöperating relations.

Similar characters of reference indicate corresponding parts in all of the views.

In the drawings, A represents the valve body or shell, comprising the two sections 1 and 2, endwise adjoined and screw-engaged or coupled together, the section 1 being adapted 40 to be coupled with the liquid-supply, while the section 2 at the upper portion thereof is coupled to the downturned extremity of the section 1 and is widened, as represented at d, whereby an inclosed chamber of sufficient area 45 is provided around the seating upper end of the valve D, which is comprised at the solid and closed end of a tube D², which makes the

nozzle or delivery end of the valve or cock, this tube being connected in the lower tubular-formed end portion of the section 2 of the 50 faucet-casing. The downturned end of the tubular or pipe-like section 1, to which the secondary section 2 is coupled, is constructed with a flaring valve-seat opening e, having an annular flaring packing f confined therein and 55 against which the rounded solid end of the valve D seats. The valve-tube D², which is guided in the tubular valve-casing section 2, is open at its forward or lower end and has ports g forward of the solid rounded valve- 60 constituting end portion.

The lower or forward tubular section 2 of the faucet-casing has at its lower or forward end portion the oppositely-located slotways h h, through which project separated studs 65 i i, which are formed as integral parts of or rigid fixtures to the valve-tube D² and through means of which connection is made between the valve-tube and the manually-actuated valve-operating devices. The valve-operating 70 devices constituting the substantial novel subject-matter hereof will be now described.

F represents a yoke-shaped or bifurcated operating-lever having the handle 10 and having in its opposite side arms 12 12, which 75 straddle at opposite sides of the downturned portion of the faucet-casing section a squared aperture 13, which fits a square lug or stud 14, projecting from the face of the eccentric 15, the screw 16 holding the eccentric pivot- 80 ally in its place at the side of the faucet-casing, the shank of the screw serving as the pivot for the center of oscillation, while the threaded extremity of the screw engages into a tapped 85 socket therefor in the side of the casing. These provisions are preferably duplicated at the opposite sides of the faucet. The swinging movement of the handle-lever imparts 90 rocking motion to the eccentric 15 through the engagement made by the formations mentioned, as shown at 13 and 14, and 18 represents an eccentric-strap, the circular aperture 19 permitting it to closely fit the periphery of the eccentric 15, this strap partaking of a

reciprocatory movement on the rolling movement of the eccentric imparted to the latter by the handle-lever.

Connection is made between the eccentric strap and the studs *i i* of the valve-tube, so that the tube will be moved in unison with the movement of the eccentric-strap, and this connection may be directly accomplished by having the eccentric-strap made sufficiently long to reach down to engage by its end perforations over the studs *i i*, (the eccentric-studs having the shape and proportions substantially as represented in Fig. 6 of the drawings,) or as the beer-cock is preferably constructed a sleeve or sheath *J* is provided to surround and inclose the lower portion of the faucet-casing, the same being by the pivots 20 20 connected with the eccentric-strap, and this sheath has connection with the studs *i i* by being formed of suitable perforations, in which the studs are closely fitted. This sheath or inclosing shell *J*, while having an up-and-down movement in unison with the valve-tube, incloses the lower delivery end portion of the faucet, preventing any of the liquid which might instead of passing through the valve-ports *g* pass down outside of the valve-tube to spray laterally from the faucet above the nozzle end of the valve-tube. This sheath, moreover, imparts a slightly and attractive appearance to the cock.

Having thus described my invention, what I claim, and desire to secure by Letters Patent, is—

35 1. In a faucet or cock, in combination, a casing-section adapted for connection with a liquid-supply, and having in its end a valve-seat opening, and a secondary casing-section adjoined and coupled to the first-named section, and open from end to end, a tube guided in said secondary section having its upper or rear end portion formed solid and adapted to close said valve-seat opening, having one or more ports, forwardly of such valve-constituting portion, through its tubular wall, an eccentric pivotally mounted at the side of the faucet-casing and capable of oscillation thereat, a lever engaged with, and for oscillating, the eccentric, and an eccentric-strap engaged 50 about the eccentric, and having a connection with the valve-tube.

2. In a faucet in combination, a casing-section adapted for connection with a liquid-supply, its end portion downturned a valve-seat opening, and a secondary casing-section adjoined and coupled to the first-named section, and open from end to end, a tube guided in said secondary section having its upper end portion formed solid and adapted to close said 55 valve-seat opening, having one or more ports forwardly of such valve-constituting portion, through its tubular wall, a pair of eccentrics

pivotedly mounted at the opposite sides of the faucet-casing and capable of oscillation thereat, a bifurcated lever engaged with, and for oscillating, the eccentrics, and eccentric-straps engaged about the eccentrics, and having a connection with the valve-tube. 65

3. In a faucet or cock, in combination, a casing-section adapted for connection with a liquid-supply, and having in its end a valve-seat opening, and a secondary casing-section adjoined and coupled to the first-named section, and open from end to end, and having a slot through its side, a tube guided in said secondary section having its upper or rear end portion formed solid and adapted to fit in said valve-seat opening, having one or more ports, forwardly of such valve-constituting portion through its tubular wall, an eccentric pivotally mounted at the side of the faucet-casing and capable of oscillation thereat, a lever engaged with, and for oscillating; the eccentric, an eccentric-strap engaged about the eccentric, a sheath surrounding the slotted portion 85 of the faucet-casing section, having connection through the slots with the valve-tube and also having connection with the eccentric-strap. 75

4. In a faucet in combination, a casing-section adapted for connection with a liquid-supply, and having in its end a valve-seat opening and a secondary casing-section adjoined and coupled to the first-named section, and open from end to end, a tube guided in said secondary section having its upper or rear end portion formed solid and adapted to close said valve-seat opening, having one or more ports forwardly of such valve-constituting portion, through its tubular wall, an eccentric arranged at the side of the faucet-casing and provided with a sidewise-projecting lug, a lever having an opening therein whereby it non-rotatably engages the lug of the eccentric, a screw passed loosely through the eccentric with a thread engagement in the faucet-casing, and having its head overlying the outer face of the lever, an eccentric-strap engaged about the eccentric, and having a connection with the valve-tube. 90 100 105

5. In a faucet in combination, a casing-section adapted for connection with a liquid-supply, and having in its end a valve-seat opening and a secondary casing-section adjoined and coupled to the first-named section, open 115 from end to end and having opposite longitudinal slots through its tube guided in said secondary section, having its upper or rear end portion formed solid and adapted to close in said valve-seat opening, having one or more ports forwardly of such valve-constituting portion through its tubular wall, eccentrics arranged at the opposite sides of the faucet-casing and provided with sidewise-projecting 120

lugs, a lever having a fork-shaped extremity, embracing the faucet-casing, provided with openings in its opposite members, whereby it non-rotatably engages the lugs of the eccentrics, screws passed loosely through the eccentrics with thread engagements in the faucet-casing, and having their heads overlying the outer faces of the lever members, eccentric-straps engaged about the eccentrics and to a sheath inclosing the lower faucet-casing sec-

tion, connected with the eccentric-straps, and studs connecting the lower opposite portions of the sheath with the valve-tube, through the aforesaid slots.
